UNITED STATES PATENT OFFICE.

GARDNER C. HAWKINS, OF WINTHROP, MASSACHUSETTS, ASSIGNOR TO CHARLES D. LANNING, OF BOSTON, MASSACHUSETTS.

COP-FORMING MECHANISM FOR SPINNING-MULES.

1,088,071.

Specification of Letters Patent. Patented Feb. 24, 1914.

Application filed June 15, 1908. Serial No. 438,484.

To all whom it may concern:

Be it known that I, GARDNER C. HAWKINS, citizen of the United States, and resident of Winthrop, Massachusetts, Suffolk county, have invented certain new and useful Improvements in Cop-Forming Mechanism for Spinning-Mules, of which the following is a specification.

This invention relates to spinning mules and more especially to that part of the mechanism of a spinning mule which has relation to the forming or building of the cop.

As is well known it is desirable to build the cops of yarn in a great variety of ways and shapes and in the standard type of mule now in use this is accomplished by means of a movable and adjustable coppering rail arranged upon the floor in such a manner as to engage mechanism on the carriage so as to control the position and movements of the winding faller.

In my present invention the coppering rail is entirely dispensed with and the whole mechanism for actuating and controlling the faller is mounted upon and carried by the mule carriage and one of the features of the invention consists in the combination with the faller of a rotary cam which by its rotation governs the movement of the winding faller on successive traverses of the carriage and means for shifting said cam to vary its relation to and action upon the faller upon successive traverses of the carriage.

Another principal feature of the invention resides in the mechanism interposed between the cop building cam and the faller which is made automatically adjustable upon successive traverses of the carriage so as to vary the initial position of the faller during the winding operation.

Another important feature consists in the combination with the faller mechanism of a special device actuated by the descent of the faller mechanism to locking position whereby the starting of the carriage running in and the winding mechanism is made to depend directly upon the movement of the faller mechanism into operative position.

These and other features of the invention will be more particularly described in the following specification, reference being had to the accompanying drawings, in which—

Figure 1 represents a side elevation of the

mule carriage showing the faller wires and the mechanism for regulating the same. Fig. 2 is a plan view of the same, a portion of the mechanism being shown in section. Fig. 3 is a front elevation of the cop building mechanism. Fig. 4 is a vertical section at right angles to the plane of Fig. 3 showing the electrical contact members. Fig. 5 is a plan view showing in detail the means for making the electrical contact when the faller is lowered. Fig. 6 is a view similar to Fig. 5 showing the electrical contacts separated, the parts of the sectional arm being disengaged. Fig. 7 is a side elevation showing the intermittent motion by which the adjustment of the faller regulating arm is secured. Fig. 8 is a detail view in central section of the click motion for actuating the faller pulling down tape.

In the accompanying drawings those parts of the mule not directly concerned with or necessary to a correct understanding of the present invention have been omitted. The mule carriage *a* mounted upon the wheels *a'* is of any suitable construction for supporting the necessary mechanism and is provided with the usual standards *a²* having upward extensions *a³* for carrying the bearings in which are supported the faller shaft *b* and the counter faller shaft *b'*. The faller arm *b²* and the counter faller *b³* are of the usual sickle shape and support the faller wire *b⁴* and the counter faller wire *b⁵* which extend lengthwise of the carriage.

The means for pulling down or depressing the faller arms *b²* may be of any suitable construction and in this case comprise a click latch device comprising a rotary pulley *c'* provided with a click latch *c²*, the pulley being mounted on the cylindrical hub or hollow stud *c³* of the hanger or standard *c⁴* which forms a support and bearing for the tin roller shaft *c*. Splined to the tin roller shaft is a ratchet wheel *c⁵* in position to be engaged by the click pawl *c²* when the shaft is turning from left to right but which is thrown out of engagement when the shaft is turning from right to left which is the direction of rotation of the shaft *c* during the spinning and winding operations, the latch or pawl *c²* being thrown out or in by means of the spring friction strap *c⁶* in a well known manner. By mounting the pulley or wheel *c'* carrying the click latch *c²* upon the

extension of the bracket c^4 , I avoid wear between the drum shaft and said wheel during the winding and spinning operation since the wheel c' is in motion only during the 5 backing off. This intermittently movable click latch wheel c' forms a cylindrical sheave upon which is wound a flexible metallic tape c^7 secured to a sector arm c^8 , which sector arm is made fast upon the faller 10 shaft b . Consequently after the spinning operation is completed when the carriage comes to rest at the end of the stretch and the tin drum shaft has been reversed for backing off the coarsely pitched spirals of 15 yarn from the spindle, the winding up of this tape c^7 upon the sheave or pulley c' operates through the sector arm c^8 to depress or swing down the faller arm b^2 , this movement obviously occurring at the same 20 time as does the backing off of the yarn.

One of the features of this invention consists in providing mechanism by which an interlocking connection is made between the descending faller arm and its regulating device. In this case the regulator by which the position of the faller wire is controlled consists essentially of an elongated tapered cam d upon which rests a roller d' which is carried by a sliding arm d^2 , said sliding 25 arm being mounted to slide vertically in a groove or channel formed in the rigid standard f that is supported upon the carriage. Obviously the rotation of the cam will cause the roller d' and the slide d^2 to rise or fall 30 according as the roller rides over the high or the low parts of the cam and by suitable connections between the slide d^2 and the faller arm a corresponding movement can be 35 imparted to the faller arm so as to give it the necessary rising and falling motions at 40 any predetermined time.

In order to form the desired engagement between the sliding arm or member d^2 and the faller, I provide a depending arm or 45 member d^3 which is supported in a pivoted lever d^4 by means of a universal joint connection d^5 , the other end of said lever d^4 having a jointed connection with an arm d^6 secured to the faller shaft b so that the 50 oscillation of the lever d^4 imparts a similar oscillation to the faller shaft to lower or raise the faller wire. Obviously if the member d^2 is provided with a pin or other device arranged to interlock with or engage the 55 member d^3 , these two parts will move as one and the vertical movement of the roller d' and member d^2 will be communicated to the faller arm. One of the features of the present invention however, consists in making 60 this engagement between these two members d^2 d^3 of the faller actuating shaft, automatically adjustable so that the two members when interlocked will form not only a connecting means between the builder cam d 65 and the faller shaft, but will also form an

automatically extensible or adjustable connection, since, if, upon each traverse of the carriage, this arm is slightly elongated, the faller wire will start slightly higher with each traverse and will finish its chase 70 at a slightly higher point on each traverse which is necessary to the proper building of a cop.

Any suitable mechanism may be employed 75 to accomplish this intermittent and consecutive lengthening of the connection between the cop building cam and the faller shaft. The device which I have herein illustrated for this purpose is constructed as follows: The slide d^2 is provided with an offset lug d^7 forming a bearing support for a screw threaded shaft e , the upper end of said shaft being free to slide vertically in a loose bearing f^2 formed on the standard f . A vertically movable traveler or nut e' has engagement with the screw threaded shaft e , so that, by the rotation of the shaft e , the nut is caused to travel in the vertical slide way, or groove formed in the standard f . This traveling nut e' carries a hollow projecting pin e^3 which projects beyond the face of the nut e' and forms one member of the locking device. The depending member d^3 is provided with a recess or socket d^8 adapted to receive the projecting end of the co-operating pin e^3 , when these two parts are 80 brought into alignment so as to interlock the nut e' and the arm d^3 . To effect this interlocking of the pin with its socket, two things are requisite; first, the member d^3 must be 85 so guided in its vertical movement that its socket d^8 will arrive opposite to the pin e^3 and, second, the pin must be pushed toward the socket or vice versa, the socketed member toward the pin. The guiding of the member, d^3 is effected by providing the nut e' 90 with projecting lugs e^4 arranged on either side of the member d^3 to prevent lateral displacement of the interlocking members with 95 relation to each other. In the second place, the depending arm d^3 is normally pressed 100 against the nut e' by means of the tension spring d^{13} , but its forward and back movement is controlled by a star wheel g , whose function and operation will be later 110 described. The lever d^{12} is also provided with laterally offset guide lugs d^{14} , which engage the external lateral faces of the nut or traveler e' . The operation of this portion of the mechanism is as follows: The sliding member d^2 is normally pulled down so that the roller d' carried by it is pressed firmly 115 against the peripheral surface of the cam d , this being accomplished by the springs d^{15} . When the faller arm is pulled down by the 120 tape c^7 , the member d^3 descends until its socket d^8 arrives opposite the locking pin e^3 , at which point the horizontal lever d^{12} operates under its spring tension to cause an 125 engagement between the socketed member d^3 130

and the nut e' . Since the nut e' is firmly connected with the slide d^2 by means of the screw threaded shaft e , it is clear that in this way the two members d^3 and d^2 are locked rigidly together, so as to form a practically continuous arm, having engagement at its lower end with the cam d through the roller d' and having engagement at its upper end by means of the link connected with the 10 faller shaft, so that the vertical movement of this sectional arm or rod $d^2 d^3$ is communicated to the faller shaft to cause the faller arm to drop when the roller is in contact with the lower parts of the cam d and 15 to rise when the roller is in contact with the higher parts of the cam d .

It will be understood that the adjustment of the nut e' vertically away from the slide d^2 serves in effect to lengthen or extend the 20 composite or sectional arm $d^2 d^3$ which may therefore be considered as an automatically extensible or adjustable means interposed between the actuating cam and the faller, the object of which construction will be 25 hereinafter explained.

Obviously a single rotation of the cam d will serve first to lower and then to raise the faller wire according to the particular shape of the cross section of the cam lying immediately beneath the cam roller d' . Hence, it will be assumed that when beginning to build the base of the cop, the cam roller d' rests upon the periphery of the cam at its small end and that upon successive traverses 35 of the carriage the cam is shifted axially or longitudinally to bring a slightly larger diameter into contact with the cam roller d' . It will be seen that the initial position of the faller on each successive traverse of the carriage will become gradually higher and higher so as to deliver the yarn at the proper height or level to form the base of the cop. By varying the shape of the cam it will be 40 possible of course to form or build a cop base of any desired shape or pitch since the 45 contour of the cam will determine the position of the faller throughout both the initial position of the faller before the winding begins, as well as its relative movement during 50 the inward traverse of the carriage.

One of the features of the invention consists in providing means for shifting the cam axially in order to vary the position and movement of the faller mechanism on 55 successive traverses of the carriage. In this case the mechanism shown is intended to shift the cam axially one step at each revolution of the cam, it being understood that the cam makes one complete revolution for 60 each inward traverse of the carriage, the cam being rotated by means of the gear wheel d^{18} secured to the cam shaft and meshing with the pinion m' on the main shaft m of the carriage. The cam d is 65 mounted to slide longitudinally of its shaft

d^{16} but is splined in the longitudinal spline groove d^{17} so as to rotate with said shaft.

Upon the gear wheel d^{18} which turns the cam shaft is secured an adjustable pin or stud d^{19} adapted to engage one end of a pivoted lever h , the other end of said lever being provided with a dog or latch h^3 to engage a ratchet wheel h' on the screw-threaded shaft h^2 which is adjacent to and parallel with the cam shaft d^{16} .

70

The lever h is normally pressed out of engagement with the latch by means of the spring h^4 while an adjustable stop screw h^5 serves to limit this outward movement of the lever h .

75

At each revolution of the gear d^{18} the adjustable stud d^{19} swings the lever h into operative engagement with the ratchet wheel h' against the tension of the spring h^4 and turns said ratchet wheel through a small arc,

80

the extent of which is determined by the position of the adjustable stud d^{19} in relation to the center of the gear d^{18} . After the stud d^{19} has passed by the spring h^4 returns the lever h to its normal position out of engagement with the ratchet.

85

The intermittently movable shaft h^2 is screw-threaded and has engagement with a heavy nut or traveler h^7 having a forked arm which engages one end of the cam as shown at h^8 .

90

The intermittent rotation of the shaft h^2 causes the arm or traveler h^7 to move longitudinally by an intermittent movement and this arm by means of its forked engagement with the cam d serves to impart a similar intermittent longitudinal movement to said cam thereby shifting the cam axially relative to the cam roller d' .

95

As the "chase" of the cop, that is the vertical distance between the lowermost winding and the highest winding of each layer of yarn, is uniform after the base of the cop has been formed, it is desired that the shifting of the cam d cease as soon as the base has been completed.

100

To this end I provide an adjustable projecting finger h^9 arranged to engage the traveler h^7 and by its upper inclined face to lift said traveler out of engagement with the screw-threaded shaft h^2 so that the shifting movement of the traveler and of the cam d shall cease

105

when the cam has reached a predetermined longitudinal position. When this traveler h^7 has thus been lifted out of engagement with the screw-threaded shaft, the rotation of the cam may continue without causing

110

any change of position longitudinally and from that time forward the rise and fall of the faller will be uniform throughout the succeeding traverses of the carriage until the entire cop is completed.

115

A further advantage resulting from this disengagement of the traveler arm h^7 from the feed shaft h^2 consists in the ability to return the cam to its initial position without consuming the time required to run it back to initial posi-

120

time required to run it back to initial posi-

125

time required to run it back to initial posi-

130

tion by reversely turning the feed shaft h^2 by hand, since when the traveler is freed from the feed shaft h^2 it is free to be pushed back to initial position and there once more dropped into engagement with the feed shaft.

Although after the completion of the cop, the "chase" or vertical height of the yarn wound on the cop on each successive traverse is uniform, nevertheless it is necessary that each successive layer of yarn on the cop from this point should begin at a slightly greater height on the cop and terminate at a slightly greater height. This object is attained by means of the continued automatic lengthening of the extensible arm d^2 d^3 which forms the connecting means between the rotating cam d and the faller mechanism as already described. Inasmuch as this lengthening of the connecting arm d^2 d^3 is accomplished intermittently on successive traverses of the carriage I have chosen to operate the adjusting mechanism therefor by means of the intermittently rotatable shaft h^2 by means which I will now describe. On this shaft h^2 is a bevel gear h^{10} which engages a bevel gear g^8 on the vertical shaft which carries at its upper end a large gear g^6 meshing with the pinion g^5 on the vertical shaft g' which carries at its top a star wheel g . The star wheel shaft g' carries a pinion intermeshing with a long pinion e^5 on the screw-threaded shaft e so that each intermittent movement of the shaft h^2 which occurs on each successive inward traverse of the carriage is communicated through the several gears and shafts secured to this long pinion e^5 and the shaft e to give a corresponding step-by-step or intermittent movement to the nut e' .

The star wheel g is so adjusted that upon its rotation the points of the star act upon the end of a horizontal lever d^{12} to throw said lever out or away from the nut e' so as to disengage the member d^3 from the projecting pin e^3 carried by the nut e' . This disengagement and separation of the interlocking members d^2 d^3 of the bootleg arm allows the faller to rise under the influence of its usual tension spring. A slight further rotation of the star wheel brings a notched or recessed portion of its periphery opposite the end of the lever d^{12} so that the lever d^{12} is free to move in again when the faller is pulled down to position with its socket just opposite the locking pin e^3 . The pinion e^5 is elongated in order to afford a continuous engagement with its driving pinion on the shaft g' without interfering with the necessary vertical movement of the shaft e .

It is important that the mechanism for running in the carriage and winding the yarn should begin as soon as the faller actuating mechanism is locked in operative posi-

tion but it is also of vital importance that these operations should not commence until that locking engagement is effected. In order to fully meet these conditions I provide an arrangement which may be utilized in any suitable manner for starting the carriage running in mechanism and the winding mechanism. To this end I have arranged two electrodes o and o^2 in the two interlocking members of the faller actuating mechanism in such a way that the proper interlocking of these parts necessarily brings these electrodes in contact whereby an electric circuit may be closed for energizing proper electrical apparatus or magnets for starting the carriage on its inward traverse to wind on the yarn. Such for example as are shown and described in my companion application Serial No. 438,460 filed of even date herewith. As this carriage driving and other mechanism forms the subject matter of my other said application, no attempt has been made to show the details of construction and arrangement. It will suffice for present purpose merely to show how the electrical circuit which controls the carriage and other movements is opened and closed by the operation of the faller mechanism.

As the details of mechanism by which the carriage is started form no part of the present invention, since any suitable electromagnet starting apparatus may be used for this purpose, I have shown only the means by which an electric circuit may be closed for such a purpose. The electrode o is carried through the hollow or tubular pin e^3 from which it is insulated by a wrapper or bushing of suitable insulating material as shown at o' . In a similar manner the electrode o^2 carried by the member d^3 is supported in and insulated from that member by means of a similar insulating bushing o^4 . The two electrodes or contact pins o o^2 are arranged so as to exactly align and form a firm contact when the member d^3 is interlocked with the nut e' . Obviously the moment these members are properly interlocked to control and regulate the faller mechanism, at the same instant an electric circuit is closed which may be utilized in setting in operation the mechanism for running in the carriage.

What I claim is:—

1. In a spinning mule the combination of the mule carriage, the winding faller, the tapered cam for actuating the faller, and means for adjusting said cam axially upon successive traverses of the carriage to vary the movement of the winding faller, and means for rendering said cam-adjusting means inoperative when the base of the cop has been completed, substantially as described.

2. In a spinning mule the combination of the mule carriage, the winding faller, a rotary cam, means interposed between the cam

70

and the winding faller to actuate the faller as the cam rotates, and means for intermittently shifting the rotary cam to vary the initial position of the faller upon successive 5 traverses of the carriage, and means for disengaging the shifting means from the cam at a predetermined stage in the building of the cop, substantially as described.

3. In a spinning mule the combination of 10 the mule carriage, the winding faller, a tapered cam mounted on the carriage, and an automatic extensible arm forming the connection between the tapered cam and the winding faller to regulate the movement of 15 said faller in order to form the cop, an adjusting screw actuated by the cam shaft for lengthening said extensible arm, substantially as described.

4. In a spinning mule the combination of 20 a mule carriage, the winding faller, the building cam, an arm actuated by said cam for actuating the faller shaft, a feed shaft, a traveling nut arranged thereon and provided with an arm for engaging said cam to 25 shift it longitudinally, and means for disengaging said arm from its operative connection between the feed shaft and the cam at a predetermined stage in the building of the cop, substantially as described.

5. In a spinning mule the combination of 30 the mule carriage, the winding faller, an actuating cam therefor, a feed screw, and a traveling nut thereon having engagement with said cam to shift the same longitudinally during the building of the cop, and means for automatically disengaging the nut from its actuating screw.

6. In a spinning mule the combination of 40 the mule carriage, the winding faller, an actuating cam therefor, means for shifting said cam automatically upon successive traverses of the carriage to properly form the base of the cop, means for rendering the shifting mechanism inoperative after the 45 base of the cop is completed, and means for varying the initial position of the winding faller for successive traverses of the carriage after the cam shifting mechanism has ceased to operate, substantially as described.

7. In a spinning mule the combination of 50 the mule carriage, the winding faller, an actuating cam mounted on the carriage, a sliding member engaged by and actuated by said cam, an interlocking member connected 55 with the winding faller, and adjustable interlocking means for forming an interlocking engagement between said members.

8. In a spinning mule the combination of 60 the mule carriage, the winding faller, an actuating cam therefor mounted on the carriage, connecting means between the cam and said winding faller, said connecting means comprising interlocking members, and means for adjusting said members relatively to each other in order to vary the in-

itial position of the faller upon successive traverses of the carriage.

9. In a spinning mule the combination of 70 the mule carriage, the winding faller, an actuating cam therefor mounted on said carriage, a cam engaging member, a link or arm connected with the winding faller, an adjustable device carried by said cam actuated member and arranged to form a locking engagement with said link or arm, and means 75 for shifting said adjustable device automatically upon successive traverses of the carriage, substantially as described.

10. In a spinning mule the combination of 80 the mule carriage, the winding faller, means for pulling down the winding faller preparatory to building the cop, a rotary cop building cam mounted on the carriage, interlocking members interposed between said cam and the winding faller, and adjustable 85 means for forming an interlocking engagement between said members when the faller has descended to its appropriate initial position.

11. In a spinning mule the combination of 90 the mule carriage, the winding faller, an actuating cam therefor mounted on the carriage, a link or arm connected with the winding faller to control its movement, a movable member having operative engagement with said cam, and a traveling nut adjustably mounted on said cam engaging member to form an interlocking engagement with said arm or link, and an intermittently actuated screw shaft arranged to 100 engage and actuate said traveling nut to adjust its position on the cam actuated member, substantially as described.

12. In a spinning mule the combination of 105 the mule carriage, the winding faller, a rotary cam mounted on the carriage for actuating said faller, a feed shaft, means operatively connecting the feed shaft with the cam for shifting the cam axially upon successive movements of the carriage and means 110 for disengaging the operative connection between the feed shaft and the cam at a predetermined position, substantially as described.

13. In a spinning mule the combination of 115 the mule carriage, the winding faller, a rotary cam for actuating the same during the winding on of the yarn, means for shifting said cam longitudinally to bring different portions of its periphery into operative position, and means for automatically disengaging the shifting mechanism after a predetermined period in order to permit the cam therefor to remain in the same operative position upon successive traverses of the carriage.

14. A cop forming mechanism embracing 125 in combination, the rotary cop forming cam, a feed shaft, a traveling arm having engagement with said feed shaft to cause it to 130

travel longitudinally, said arm having engagement with said cam to move said cam longitudinally, and means for releasing said arm from its engagement with the feed shaft, substantially as described.

15. In a spinning mule the combination of the mule carriage, the winding faller, faller actuating mechanism comprising interlocking members, and means whereby the starting of the carriage is effected by and dependent upon the interlocking of said members, substantially as described.

16. In a spinning mule the combination of the mule carriage, the winding faller, faller actuating mechanism for controlling and actuating the faller, and electric conductors arranged to be brought into contact with each other by the faller mechanism to close a circuit controlling the carriage driving mechanism, substantially as described.

17. In a spinning mule the combination of the mule carriage, the winding faller, a cop former for building the cop, means for locking the faller in operative relationship to said cop former, said locking means being provided with electrodes which are brought into contact thereby for the purpose of causing the carriage driving and the winding

mechanism to be set in operation, substantially as described.

18. In a spinning mule the combination of the mule carriage, the winding faller, cop building mechanism for controlling the winding faller, and a device for controlling the carriage driving mechanism, said controller being connected with the faller actuating mechanism whereby it is rendered operative by the movement of said faller actuating mechanism.

19. In a spinning mule the combination of a mule carriage, the winding faller, cop building mechanism by which the winding faller is controlled, electrical conductors for carrying a circuit by which the carriage driving mechanism is controlled, the terminals of such circuit being connected with the faller actuating mechanism by which the opening and closing of said controlling circuit is governed by the movement of the faller mechanism substantially as described.

In witness whereof, I have subscribed the above specification.
